UNITED STATES PATENT OFFICE

LOUIS F. McKELVEY, OF INDIANAPOLIS, INDIANA

DISPLAY RACK

Application filed September 20, 1930. Serial No. 483,202.

My invention relates to display stands, such as are used for the display of greeting cards.

There are several methods now used for displaying such articles as greeting cards, and all of these methods have certain disadvantages which are not present in a method which involves using my invention. The greeting cards are sometimes left in the boxes 5 in which they come and these boxes are arranged on a flat surface, which takes up a considerable amount of space for the display of a relatively small number of cards. Sometimes the cards are taken out of their boxes 10 and arranged in vertical position in a rack comprising a series of stepped shelves or tiers of card-compartments; but the cards, having their upper edges unprotected, very often get dirty, have their edges bent, or are otherwise rendered unfit for sale. Further, in such an arrangement, each card is partially obscured by the group of cards ahead of it. Again, even though these racks may be arranged to receive various different sizes of 15 cards, their usefulness is considerably hampered because many cards are of odd sizes which will not fit the compartments provided, and the sizes and shapes of cards vary widely. Moreover, when the cards are arranged in such a rack it is necessary for a prospective purchaser to handle a large number of cards in making his selection.

It is the object of my invention to provide a display stand which will permit the display of a relatively large selection of cards in a minimum amount of space, and in which the boxes containing the cards may be arranged with practically no limitations. By being left in their boxes, the cards are all protected against having their edges bent or getting dirty. Also, by my novel arrangement of shelves, the cards on one shelf are somewhat protected by the overhanging portion of the shelf above while at the same time the cards are all fully exposed to the view of prospective purchasers. In case the boxes containing the cards are too large to be contained in the shelves, they may be set up at the front of one shelf against the front edge 20 of the one just above.

An embodiment of my invention is illustrated in the accompanying drawing; in which: Fig. 1 is a perspective view of a display stand showing the arrangement of boxes on one of the shelves; Fig. 2 is a vertical transverse section showing the relative position of the shelves; and Fig. 3 is a somewhat diagrammatic section similar to Fig. 2 but showing a different arrangement of shelves. 55

Devices embodying my invention may be 60 made of any material; but I contemplate making them of sheet-metal, and have shown a device so made in the drawing.

In this display stand, there are two end walls 10, desirably provided with flanges 11 65 at their rear edges which are integral with the walls 10 and extend toward each other at right angles to the walls. The flanges 11 are conveniently attached at their lower ends to a length of angle iron 17 which serves to hold 70 the side walls 10 in proper spaced relation. The flanges 11 and angle iron 17 provide desirable reinforcements for the side walls 10 and the display stand as a whole.

The side walls 10 are substantially in the 75 shape of a right triangle, but they may be in the shape of a triangle other than a right triangle, or of a frustum of a triangle.

Between the two end walls 10 there are a plurality of shelves 12. Each of these shelves 80 is conveniently made of a single sheet of metal, which has its longitudinal edges turned upward at substantially right angles to the bottom of the shelf to form a front flange 13 and a back flange 14. The ends of each shelf 12 and of the back flange 14 are conveniently provided with down-turned edges 15 either over their whole width or over part of their width, as is clear from Fig. 2. These down-turned edges 15 are of advantage in securing 85 the shelves to the side walls 10.

The shelves 12 are disposed between the end walls 10 so that they are transversely inclined; that is, they are put on an angle so 90 that the contents of all the shelves are clearly visible from in front of the stand and so that it is unnecessary for a prospective purchaser to handle the cards or the boxes containing the cards in making a selection.

In order to provide this accessibility and 100

fullness of display and at the same time conserve space, the shelves 12 are arranged in overlapping stepped relation. The front edge of the end walls 10—the hypotenuse edge of a triangular end wall—provides a convenient basis for the alining of the shelves. The shelves are put in place with the upper edges of their front flanges 13 alined with and adjacent to the front edges 10 of the end walls 10, and are so spaced and so inclined that the back flange 14 of any one of the shelves except the top shelf projects toward and abuts the bottom of the shelf just above along a longitudinal line near the middle of that shelf. In this manner each shelf 15 overhangs the shelf below it and thus provides for the contents of that lower shelf a certain degree of protection from dust.

Each shelf, however, is set back from the 20 position of the one just below it, which aids in making the contents of all the shelves visible. In the event that a box desired to be put on a shelf is too large, this set back arrangement permits that box to be set up in 25 front of the shelves resting in the groove provided by the bottom and the front flange 13 of a shelf, and leaning against the front of the shelf just above, as is clear from Fig. 3.

The top one of the series of shelves 12 is 30 not provided with a back flange 14 as are the lower shelves, but the back edge of this top shelf is bent downward so that it will lie in a vertical plane when the shelf is in place, and is then bent back upon itself to provide 35 a groove 16 in which indices of the cards and prices may be supported.

It may be desirable, instead of having all the shelves at the same inclination, to have the shelves at different inclinations, as for 40 instance to have each succeeding shelf from the bottom shelf upward at a slightly greater inclination than the one below it. I have illustrated a stand with shelves so arranged in Fig. 3. By this arrangement, all the cards which are placed on the shelves will be more 45 nearly perpendicular to the line of sight of a prospective purchaser.

I claim as my invention:—

1. A display stand, comprising end walls, 50 a plurality of forwardly and downwardly inclined shelves extending between said end walls, a front flange on each of said shelves, some of said shelves being provided respectively with back flanges, each of said back 55 flanges extending generally upwardly from the rear edge of its associated shelf and abutting the bottom of the shelf next above on a line intermediate the longitudinal edges thereof, said shelves being successively set-back from the bottom of the stand toward the top, whereby the front edge of each shelf projects forwardly beyond the shelf immediately above it.

2. A display stand as defined in claim 1 the 60 shelves of which have successively increased 65

inclinations to the horizontal, the bottom shelf having the least inclination.

In witness whereof, I have hereunto set my hand at Indianapolis, Indiana, this 17th day of September, A. D. one thousand nine hundred and thirty.
